United States Patent Office

Des. 182,388
Patented Mar. 25, 1958

182,388

CHAIR OR THE LIKE

Sol Sigal, Brooklyn, N. Y., assignor to Phoenix Metal
Parts Corp., Brooklyn, N. Y., a corporation of New York

Application May 8, 1957, Serial No. 46,073

Term of patent 3½ years

(Cl. D15—8)

FIG. 1.

FIG. 2.

FIG. 3.

FIG. 4.

The characteristic features of my design reside in the portions shown by means of full lines in the drawing.

I claim:

The ornamental design for a chair or the like, as shown and described.
